[57] CLAIM

The ornamental design for the directional flow structural tee, as shown and described.

DESCRIPTION

FIG. 1 is an isometric view of the first embodiment of a directional flow structural tee, showing my new design;
 FIG. 2 is a top plan view;
 FIG. 3 is a right side view, the left side view being a mirror image thereof;
 FIG. 4 is a bottom plan view;
 FIG. 5 is a front view;
 FIG. 6 is a rear view;
 FIG. 7 is an isometric view of the second embodiment of a directional flow structural tee, showing my new design;
 FIG. 8 is a top plan view;
 FIG. 9 is a right view, the left side view being a mirror image thereof;
 FIG. 10 is a bottom plan view;
 FIG. 11 is a front view; and,
 FIG. 12 is a rear view.
